UNITED STATES PATENT OFFICE

HERMANN WEBER, OF SPIEZ, SWITZERLAND

FEEDING DEVICE

Application filed March 26, 1930, Serial No. 439,257, and in Germany June 18, 1929.

This invention relates to a device for feeding liquid or gaseous fluids by means of an eccentrically supported piston and a radially directed blade or a plurality of such blades, 5 extending from said piston into the casing thereof. Feeding devices of this type suffer firstly, from the difficulty of keeping said rotary piston in its casing or cylinder tight, in that leakages arise in the case of a def- 10 ormation of the casing or cylinder, and secondly, from the difficulty of preventing the blade from jamming in its chamber in such case. It is to be borne in mind that blades arranged in the above-stated manner not only 15 reciprocate, but also oscillate when the eccentrically supported piston is in motion, and that, owing to the very great number of revolutions of feeding devices of the type in question, viz. up to 2000 revolutions per 20 minute, the generation of frictional heat is very great which is another and somewhat frequent cause for jamming. If a feeding device of this type is used in connection with, or for, a compressor, the heat of compression 25 constitutes an additional cause for jamming. From these and other reasons feeding devices with an eccentrically supported piston have even up to the present time not been generally approved in spite of the ad- 30 vantages presented by the rotary motion of the driving member or members.

The difficulties stated in the preceding paragraph are encountered especially if the pivot of the blade in the casing is stationary 35 and the blade is shiftable in this stationary pivot. In such case a considerable accumulation of heat in that pivot takes place, and this entails the necessity of either making the pivot bearing particularly large or of pro- 40 viding cooling means for it. The heat accumulation is smaller if the pivot is located in the blade itself and this latter is arranged in a slide guided in the casing, in that in this case the heat is abstracted throughout 45 the entire length of the slide guide.

Hitherto the pivot of the blade has always been undivided, which necessitates a comparatively long guide path for the bearing in the casing whereby tightening or pack- 50 ing the piston with respect to the cylinder

is rendered difficult. The longer the guide path, the more easily is it possible that the cylinder becomes deformed when a high feeding pressure is used, and further detrimental consequences are that the tightening or pack- 55 ing of the piston at the cylinder wall and the efficiency of the device are unfavorably influenced. Besides, the lubrication of the pivot is rendered more difficult, as the lubricant easily becomes hardened by the heat. 60 Furthermore, the closed bearing is subject to a comparatively great expansion by reason of its large bulk which is also a cause for jamming if it is accurately fitted into its 65 guide path.

All these difficulties are completely done away with by my present improved feeding device, the main characteristic feature of which resides in that the bearing for the pivot of the blade located at the piston is formed by two lateral members which I have termed 'shoes' and which are not connected with one another in any way. This invention is illustrated diagrammatically and by way of example in the accompanying drawings in which Figure 1 is a vertical section through a feeding device designed according to this invention, the section plane standing at right angles with respect to the cylinder axis; Figure 2 is another vertical section, the plane of 70 which stands at right angles to that of Fig. 1; Figure 3 is a modification, drawn to a much larger scale, of the sliding bearing for the blade, located in the blade guiding chamber (compare therewith the middle portion of the lower half of Fig. 1); and Figure 4 is a 75 separate view of one of the shoes (20) of Fig. 3, seen from the inner face thereof.

The cylinder of the device consists of a chiefly hollow member 1 which is open at both sides and is there closed by covers 2 and 3 connected with the member 1 and with one another by bolts 4. The main part of the hollow space in the member 1 is cylindrical, that is to say, constitutes the cylinder, and a shaft 5 extends coaxially with this cylindrical space through it and through the covers, to one end of which shaft is attached a small pulley 6. To the shaft 5 is affixed, within said cylinder, an eccentric member 7 support- 80 85 90 95 100

ing an annular piston 8, the periphery of which contacts with the peripheral inner wall of the cylinder, as shown in Fig. 1. The arrow in this figure indicates the direction of 5 rotation of the member 7.

9 is a blade which is attached to the piston in the manner shown in Fig. 1 and takes part in the reciprocating, as well as in the oscillating motion of the piston 8. While the piston 10 8 is oscillating, as well as reciprocating vertically, so as to move the blade 9 up and down in the chamber 10 provided for it in the member 1, all successive portions of its peripheral surface contact successively with all successive 15 portions of the inner peripheral wall of the cylindrical space in the member 1, in consequence whereof the sickle-shaped working spaces or chambers 11 and 12 are continually and alternately increased and decreased. 11 20 is the suction chamber, 12 the pressure or delivery chamber. The chamber 11 receives the respective fluid through the suction valve 15, the intermediate space 14 and the passage 13, and from the chamber 12 the fluid escapes 25 through the passage 16 and past the delivery valve 18 into the space 17 from which it is further conveyed away.

Now, the pivot portion 19 of the blade 9 is tightly fitted between two shoes 20 having 30 each a concave side contacting with said pivot portion, and a flat side contacting with one of the flat walls of the chamber 10 in which the blade, or its pivot portion with the shoes respectively, moves up and down, the blade 35 at the same time also moving to and fro in the plane of the piston 8, and its pivot portion turning to and fro between the shoes.

The blade 9 is provided with lubricating channels 23 and 24 (Figs. 1 and 3), as well as 40 with a lubricating passage 21 shown in dotted lines in Fig. 3. This latter passage communicates with the chamber 10 into which the lubricant is introduced through a bore 25 (Figs. 2 and 3). The lubricant is sucked into 45 this chamber and further into said passages so as to lubricate the blade everywhere, including the shoes, and the sucking action is effected by the vertical reciprocations of the piston 8 with the blade 9.

50 The length or height of the guide faces in the chamber 10 for the shoes need only be very moderate so that the casing 1 need not be extraordinarily high, and owing thereto the great feeding or conveying pressure produced 55 by the respective fluid while the feeding or conveying is going on cannot deform the casing 1 in that this latter is fully able to stand them.

In order to reduce the friction arising between the shoes and the walls of the chamber 60 10 ball-bearings or roller bearings 22 (Figs. 3 and 4) can be provided, the balls or rollers contacting, of course, with the respective walls. The circumference of the balls or 65 rollers is preferably a little more than the

length of the stroke of the blade 9 so that non-uniform wear and tear of the rollers or balls is prevented.

I claim:

1. A feeding device for liquid or gaseous fluids, comprising, in combination, a casing 70 having a cylindrical space; an annular piston arranged eccentrically in said space; an eccentric located in said piston; means for rotating said eccentric; a blade extending from said piston into a chamber provided for it in said casing, the blade-portion most remote from the piston being designed as a pivot for it; and two independent shoes enclosing this pivot-portion of the blade between them and guiding it between the walls of said chamber, said blade portion having a passage therein for lubricant, said passage running lengthwise of the blade, and a plurality of other lubricant passages communicating therewith and terminating adjacent the shoes, to feed lubricant to said shoes and thus also assist in maintaining fluid-tight joints substantially as and for the purposes set forth. 80

2. A feeding device for liquid or gaseous fluids, comprising, in combination, a casing 90 having a cylindrical space; an annular piston arranged eccentrically in said space; an eccentric located in said piston; means for rotating said eccentric; a blade extending from said piston into a chamber provided for it in said casing, the blade-portion most remote from the piston being designed as a pivot for it two independent shoes enclosing 100 this pivot-portion of the blade between them and guiding it between the walls of said chamber; and rotary antifriction members inserted into said shoes on the side where they contact with the chamber walls, and substantially enclosed by said shoes, said blade portion having a passage therein for lubricant, said passage running lengthwise of the blade, and a plurality of other lubricant passages communicating therewith and terminating adjacent the shoes, to feed lubricant to said shoes and thus also assist in maintaining fluid-tight joints substantially as and for the purposes set forth. 110

3. A feeding device for liquid or gaseous fluids, comprising, in combination, a casing 115 having a cylindrical space; an annular piston arranged eccentrically in said space; an eccentric located in said piston; means for rotating said eccentric; a blade extending from said piston into a chamber provided for it in said casing, the blade-portion most remote from the piston being designed as a pivot for it; two independent shoes each 120 bounded by a substantially hemi-cylindrical surface on one side and by a plane surface on the other; the chamber into which said blade projects being likewise provided with plane surfaces engaging the plane surfaces of the 125 shoes, the said cylindrically curved surfaces 130

being in contact with portions on the blade which are given the same curvature so as to make a tight joint therewith, said blade portion having a passage therein for lubricant,
5 said passage running lengthwise of the blade, and a plurality of other lubricant passages communicating therewith and terminating adjacent the shoes, to feed lubricant to said shoes and thus also assist in maintaining
10 fluid-tight joints, substantially as and for the purposes set forth.

In testimony whereof I affix my signature.
HERMANN WEBER.
